UNITED STATES PATENT OFFICE.

THOMAS R. DU BOIS, OF NIAGARA FALLS, NEW YORK, ASSIGNOR TO U. S. LIGHT & HEAT CORPORATION, OF NIAGARA FALLS, NEW YORK, A CORPORATION OF NEW YORK.

STARTING AND LIGHTING SYSTEM.

1,367,804.

Specification of Letters Patent.

Patented Feb. 8, 1921.

Application filed August 28, 1916, Serial No. 117,190. Renewed June 23, 1920. Serial No. 391,157.

To all whom it may concern:

Be it known that I, THOMAS R. DU BOIS, a citizen of the United States, residing at Niagara Falls, in the county of Niagara and State of New York, have invented new and useful Improvements in Starting and Lighting Systems, of which the following is a specification.

The present invention relates to starting and lighting systems.

In certain starting and lighting systems for automobiles, it has been proposed to use dynamo-electric machines having both motoring and generating functions, which machines are provided with a plurality of winding circuits connected in parallel during the motoring operation for the purpose of delivering a high torque, certain of which circuits are cut out during the generating operation. The present invention relates to improvements in systems of this variety.

One object of the present invention is to provide an engine starting and lighting system involving dynamo-electric machinery having both motoring and generating functions which will re-start the automobile engine if it tends to stall.

A further object is to provide a starting and lighting system for automobiles involving in a novel manner a non-stall switch whereby the automobile engine will be restarted if it tends to stall.

In certain non-stall systems for automobiles, there is a wide range of speed within which the storage battery will tend to drive the automobile through the engine crank shaft, resulting in a severe drain on the battery. A further object of the present invention is to minimize this drain.

Further objects will be apparent as the description proceeds.

Referring now to the drawings—

Figure 1 represents one embodiment of the present invention.

Fig. 2 represents a modified embodiment.

Referring first to Fig. 1, the numeral 1 represents a dynamo-electric machine having both motoring and generating functions. The dynamo-electric machine illustrated in Fig. 1 is of the type described and claimed in the application for United States Letters Patent Serial No. 856,805, filed August 14,

1914, by Lewis W. Nelson, or the modification thereof described and claimed in the application for United States Letters Patent Serial No. 29,067, filed May 19, 1915, by William A. Turbayne and Thomas R. Du Bois, said dynamo-electric machine comprising a stationary field magnet 2, herein illustrated as a 6-pole magnet. Surrounding said field magnet is a ring-wound rotatable armature 3. Coöperating with the ring winding of the armature are six fixed brushes, 4, 5, 6, 7, 8 and 9, of these brushes, 4, 6 and 8 are of like polarity, illustrated as positive, whereas the intermediate brushes 5, 7 and 9 are of the opposite polarity. Brushes 4, 6 and 8 are connected by a conductor of low resistance whereby said brushes will be of the same potential. Brushes 5 and 9 are also connected by a conductor of low resistance, whereby said brushes 5 and 9 will be of the same potential. The field magnet is provided with six salient poles, 10, 11, 12, 13, 14, and 15. Of these poles, poles 10, 11, 12, 13 and 14 are provided with a series field winding 10^a, connected in series with the outside circuit of the dynamo-electric machine. Pole 15 is provided with a shunt winding 15^a which is illustrated as being connected between one terminal 16 of the series winding on the pole 14 and the negative brush 7. The terminal 16 of the series winding is connected by means of a conductor 17 with the positive terminal of the storage battery 18. The negative side of the battery is connected to the negative brushes of the dynamo-electric machine through circuits which are presently to be described. Across the terminals of the storage battery 18 is a lighting circuit 19.

Connected to the negative brushes 5 and 9 is the conductor 20, leading to the fixed contact 21. Coöperating with the fixed contact 21 is the fixed contact 22. These contacts are adapted to be bridged by the switch 23. Said switch 23 is adapted to be operated by the magnetic core 24 which is responsive to the energization of the winding 25. The conductor 26 connects the negative side of the storage battery with the fixed contact 22.

Connected with the negative brush 7 is a conductor 27 leading to the pivot point 28

of a manually operable switch 29. Coöperating with the switch 29 are two fixed contacts 30 and 31. Contact 30 is connected by the conductor 32 to one side of the winding 5 25, the other side of said winding being connected to the conductor 26.

A magneto for supplying the engine ignition is represented by the numeral 33. When the switch 29 is thrown into contact with 10 contact 31, the magneto 33 will be short-circuited and rendered inoperative.

When the operator desires to start the automobile engine, not shown, he will close the switch 29 on contact 30, thereby completing a circuit from the positive side of 15 the storage battery, through the conductor 17 to the point 16, through the shunt field winding 15^a to the conductor 27, through switch 29, conductor 32, winding 25 and conductor 26, back to the negative side of 20 the storage battery. From the point 16, current will also pass through series winding 10^a to the brushes 6 and 8 to the brush 7, passing through the coils of the ring-wound 25 armature interposed between brushes 6 and 7 and 8 and 7. From the brush 7 current will pass through the switch 29 and winding 25, back to the negative side of the storage 30 battery. The passing of current through the winding 25 will close the switch 23 on the contacts 21 and 22. In addition to the 35 circuits just traced, current will now pass over the following circuit: from the positive side of the storage battery to the point 16, through the series winding 10^a to the brushes 4, 6 and 8 and through the intervening coils of the ring-wound armature to the negative brushes 5 and 9, thence passing through conductor 20, switch 23 to the 40 negative side of the storage battery. All of the armature coils will now be energized in parallel circuits, and the series winding 10^a will be connected in parallel with the shunt winding 15^a. The parallel circuits will act 45 cumulatively to develop a high torque for starting purposes. After the automobile engine becomes self-actuating, it will drive the dynamo-electric machine as a generator, developing a voltage across positive brushes 50 6 and 8 and negative brush 7. The field energization of the dynamo-electric machine will be derived from the shunt coil 15^a and the E. M. F. developed will be the algebraic sum of the E. M. F.'s developed in the armature coils between brushes 6 and 8. The 55 energization due to the series field winding 10^a will be practically negligible, for the reason that the amperage, when the machine is operating as a generator, will be relatively small and the series winding will be composed of a relatively small number of turns. Furthermore, the E. M. F.'s developed in the coils of the ring-wound armature, except those adjacent the shunt wound pole, will cancel out,

due to the alternate arrangement of positive 65 and negative field poles. The particular dynamo-electric machine illustrated will have a valuable self-regulating action, but as such regulating action constitutes no part of the present invention, no explanation will be 70 given herein of said regulating action.

As the E. M. F. developed by the dynamo-electric machine increases, due to the increased speed of said automobile engine, the difference between the generator voltage 75 and the battery voltage will decrease, thereby decreasing the energization of the winding 25 which will allow the switch 23 to open. The dynamo-electric machine will continue to be operated by the automobile 80 engine and will charge the storage battery through a circuit extending from the positive brushes 6 and 8 through the series winding 10^a to the point 16, conductor 17, storage 85 battery 18, winding 25, conductor 32, switch 29, to negative brush 7. The coils in the arc including brushes 6, 5, 4, 9 and 8, it will be noted, are out of circuit at this time.

Should the automobile engine tend to stall, resulting in a material decrease in speed of 90 the dynamo-electric machine, current will pass from the storage battery through the dynamo-electric machine and winding 25, back to the storage battery, acting to again close switch 23 and again energize all the 95 coils to operate the dynamo-electric machine as a motor to start the automobile engine.

The operator will leave the switch 29 in contact with the contact 30 as long as he desires his engine to operate. When he desires to stop his engine, he will swing switch 29 out of contact with contact 30 and into contact with contact 31, thereby opening the circuit of the dynamo-electric machine and closing a short circuit around the magneto 105 33, thereby rendering said magneto inoperative.

It will be noted from the above description that while the dynamo-electric machine is operating as a generator to charge the 110 storage battery and supply the lighting circuit 19, the switch 23 will be open. The winding 25 will be so designed that it will be unable to close the switch 23 while the charging current is passing therethrough. The 115 discharging current from the storage battery to the dynamo-electric machine will be much heavier than the charging current. Actuated by such discharging current, the winding 25 will be sufficiently energized to 120 close said switch 23.

The manner in which the embodiment of the present invention disclosed in Fig. 1 will minimize the drain on the storage battery will now be explained. By way of 125 example it may be assumed that the dynamo-electric machine will be operative to supply the battery and the lights when the

automobile is running at a speed of ten miles an hour or more. It may also be assumed that the engine will tend to stall when the speed, on high gear, is reduced to 5 two miles per hour. In the non-stall systems now in use, though there is no necessity for drawing on the battery between the speeds of two and ten miles per hour, the battery will be discharging current to 10 the dynamo-electric machine to drive same as a motor, thus helping to drive the automobile—an uneconomical procedure. According to the present invention, the winding 25 may be designed to close the switch 15 23 only when the automobile speed is reduced to nearly two miles per hour. Between the speeds of two and ten miles per hour, therefore, the greater part of the parallel armature circuits will be cut out of 20 circuit and the battery may discharge through only the armature windings embraced by brushes 6, 7 and 8. Only when the engine tends to stall and needs energy from the battery will the switch 23 close 25 to throw in circuit the parallel branches of the armature windings. The figures chosen, it will be understood, are taken merely by way of example.

Referring now to the embodiment of the 30 invention disclosed in Fig. 2, a different type of dynamo-electric machine is represented. The dynamo-electric machine shown in Fig. 2 is of the type described and claimed in an application of William 35 A. Turbayne for United States Letters Patent No. 7, 586, filed February 11, 1915. The dynamo-electric machine is provided with two armatures, one of which for convenience, may be referred to as a generator 40 armature and the other of which may be referred to as a motor armature. Under motoring conditions, said armatures are energized in parallel circuits and act cumulatively through suitable transmission means 45 to supply a high torque for starting purposes. Under generating conditions, only the generator armature is employed, the motor armature being open-circuited and suitable means being provided whereby the 50 motor armature is thrown out of driving relation with said generator armature. The dynamo-electric machine is provided with a field frame 34 and two armatures 35 and 36. The armature 35 will be provided with a 55 low resistance winding and is the one above referred to as the motor armature. The armature 36 will be provided with a high resistance winding and is the one referred to above as the generator armature. The 60 field frame 34 is provided with series coils 37, 37. Connected across the brushes of the high resistance generator armature 36 is a shunt field winding 38. A bucking coil 39 is connected in the charging circuit to cut 65 down the field excitation as the current out-

put of the armature 36 tends to increase. The switch 23 is identical with the switch 23 disclosed in Fig. 1. One side of the series field winding 37 is connected with the contact 21. The other side of the series 70 field winding 37 is connected through the low resistance motor armature to the positive side of the storage battery 18.

When the operator desires to start the automobile engine in the embodiment of the 75 invention disclosed in Fig. 2, he will close switch 29 on the contact 30, thus completing a circuit from the positive side of the storage battery 18 through high resistance armature 36 and shunt winding 38 in parallel to 80 the point 40, thence through the bucking coil 39 (which will now act cumulatively with shunt coil 38), switch 29 and winding 25 to the negative side of the storage battery. The flow of current through winding 25 85 will be sufficient to close the switch 23, thereby completing a second circuit as follows—from the positive side of the storage battery, through low resistance armature 35, series field windings 37, 37, contact 21, 90 switch 23, contact 22, to the negative side of the storage battery. The two armatures, it will be noted, are now connected in parallel and will act cumulatively to supply a high torque to start the automobile engine. 95 As the engine becomes self operative, it will drive the high resistance generator armature 36 to set up an opposing E. M. F. to the E. M. F. of the battery. The resulting decreased energization of the winding 25 100 will cause the switch 23 to open, thereby opening the circuit through series winding 37 and low resistance armature 35. The armature 36 will supply the charging current through winding 25 to charge the storage battery and to supply the lighting circuit 19. The field excitation will be supplied by the shunt field coil 38, regulation being accomplished by the bucking coil 39. If the engine should tend to stall, resulting 110 in a slowing down of the armature 36, the battery will send a sufficiently high current through winding 25 to close switch 23, again causing the dynamo-electric machine to act as a motor to start the automobile 115 engine.

The example cited above relative to Fig. 1, will apply also to the embodiment disclosed in Fig. 2. Assuming, as before, that the dynamo-electric machinery will be operative to charge the battery when the automobile is running at a speed of ten miles an hour and that the engine will tend to stall when the automobile, running on high gear, is running at two miles per hour, there 120 will be the range of speeds between two and ten miles per hour during which the dynamo-electric machinery is developing insufficient voltage to overcome the back E. M. F. of the battery, but during which 130

- the engine is perfectly operative to drive the car. According to the present invention, during such period only the high resistance armature circuit 36 will be connected to the battery, the low resistance parallel armature circuit 35 being disconnected by the switch 23. In practice, the discharge through said high resistance armature circuit will be so low as to be negligible.
- 10 Two embodiments of the present invention have been described in detail to illustrate its adaptability to two types of dynamo-electric machinery. The invention may take various forms and may be applied to other types of dynamo-electric machinery in which a portion of the windings are used to furnish current, which windings are used cumulatively with the remaining windings under motoring conditions. It is desired 15 to cover in this case all modifications that fall within the scope of the invention as defined by the appended claims.
- Having described my invention, what I claim as new and desire to secure by Letters 20 Patent of the United States is—
1. In a starting and charging system in combination, dynamo electric machinery having both generating and motoring functions, a storage battery, said dynamo electric machinery having armature windings adapted to be connected to said storage battery for starting purposes and means connected in series between said battery and part only of said armature windings for connecting said battery across all of said 25 armature windings.
2. In combination, dynamo electric machinery having a plurality of armature circuits, a storage battery and means responsive 30 to a predetermined motoring current delivered to said machinery by said battery to connect all of said armature circuits in circuit with said battery, said means being biased to disconnect certain of said circuits 35 from said battery.
3. In combination, dynamo electric machinery having a plurality of armature circuits adapted to be connected in parallel, a storage battery and means responsive 40 to a relatively heavy motoring current delivered to said machinery by said battery to connect all said armature circuits in circuit with said battery, said means being biased to disconnect certain of said 45 circuits from said battery.
4. In combination, dynamo electric machinery, adapted to perform either motoring or generating functions, said machinery being provided with a plurality of armature exciting means, all of which are operative 50 during motoring and only part of which are operative during generating, a storage battery and means responsive to the difference of potential between said machinery and
- said battery for governing the remainder of 65 said armature exciting means.
5. In combination, dynamo electric machinery adapted to perform either motoring or generating functions, said machinery being provided with parallel armature circuits, a storage battery and means responsive to the difference of potential between 70 said machinery and said battery for determining whether or not said armature circuits shall act accumulatively.
6. In combination, dynamo electric machinery adapted to perform either motoring or generating functions said machinery being provided with a plurality of armature exciting means adapted to act cumulatively during the motoring period but only part of which is adapted to be operative during the generating period, a storage battery connected to said machinery and means for rendering the remainder operative 85 should the E. M. F. developed by said machinery fail.
7. In combination, dynamo electric machinery adapted to perform either motoring or generating functions, said machinery being provided with a plurality of armature exciting means adapted to act cumulatively during the motoring period but only part of which is adapted to be operative during the generating period, a storage battery connected to said machinery and means connected in series between said machinery and said storage battery for rendering the remainder operative should the E. M. F. developed by said machinery fail.
8. In combination, dynamo electric machinery having both generating and motoring functions and provided with a plurality of armature circuits, a storage battery and means responsive to the difference of potential between said battery and the E. M. F. set up by certain circuits for connecting said battery to deliver motoring current to all of said circuits.
9. In combination, dynamo electric machinery having both generating and motoring functions and provided with a plurality of armature exciting circuits which act cumulatively under motoring conditions but of which only a portion are operative under generating conditions, a storage battery and means responsive to the voltage produced by said portion for governing the remainder of said circuits.
10. In combination, dynamo electric machinery having both generating and motoring functions and provided with a plurality of armature exciting circuits which act cumulatively under motoring conditions but of which only a portion are operative under 115 generating conditions, a storage battery and means in series between said machinery and generating conditions, a storage battery and said battery for governing the remainder of said circuits.

11. In combination, dynamo electric machinery adapted to be connected to an internal combustion engine for starting same and also to be driven by same, said machinery being provided with a plurality of armature exciting circuits which act cumulatively under starting conditions but of which only a portion are operative when said machinery is being driven by said engine and means operative when said engine tends to stall to control the remainder of said armature circuits.
- 5 In witness whereof I have hereunto subscribed my name.

THOMAS R. DU BOIS.
